POWER OPERATED CASE SHIFT MECHANISM FOR TYPEWRITING MACHINES

Ronald D. Dodge, Poughkeepsie, N. Y., assignor to International Business Machines Corporation, New York, N. Y., a corporation of New York

Application November 10, 1944, Serial No. 562,789

9 Claims. (Cl. 197—74)

1

This invention relates to typewriting machines. The principal object of the present invention is to provide an improved power operating mechanism for typewriting machines.

An object is to provide a power operating mechanism which is smoother and more positive in its action upon the devices operated thereby.

An object is to provide a power operating mechanism which actuates positively in both directions instead of positively in one direction with immediate restoration by a spring in the other direction.

An object is to provide a power operating device for typewriting machines which is especially suitable for operating the shift mechanism.

An object is to provide a power operated shift mechanism which is simpler, more positive, and quieter in its operation than power shift mechanisms heretofore used.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a vertical section through a power mechanism embodying the present invention showing the parts of the power mechanism in the normal position.

Fig. 2 is a vertical section showing certain of the parts in partly operated position.

The invention is shown in the drawings as applied to the well-known "Electromatic" typewriter. It will be understood, however, that the invention is not limited in its application to the specific form of typewriter selected for purposes of illustration but may be applied to other typewriters equally as well.

In the well-known "Electromatic" typewriter the power mechanism comprises a main power roller which is designated 10 in the drawings with which cooperates a series of cam units, each controlled by a key and connected to operated devices such as type bars, the shift mechanism, the carriage return mechanism, and so on. The present invention contemplates making use of this main power roller 10 in conjunction with a second power roller and a modified form of cam unit to obtain a smoother and more positive operation of devices in such machines, particularly the shift mechanism which ordinarily is fairly noisy on account of the mass of mechanism which must be moved by the shift cam unit to effect the shifting of the type bars from one case position to the other.

2

In Fig. 1 the numeral 11 designates a portion of the type basket which is mounted on leaf springs 12 in a well-known way and which includes an adjustable stop 13 comprising a headed screw threaded into a lug 11a forming part of the type basket. The head of the screw 13 limits movement of the basket to its upper position, in which the lower case characters will be printed, by co-operation with a stop post or strip 14 secured to the main frame work, the post being provided with a hole through which the shank of the screw 13 passes. There are four of the springs 12 arranged in two pairs at the sides of the machine to form parallel motion links which cause the type basket to move in substantially a straight line through the relatively short distance necessary to affect a change in case. The stop screw 13 carries a threaded collar 15 which limits the downward movement of the type basket to the upper case position by engaging the upper side of the post 14. It will be understood that there are two of the stop screws 13 and two of the posts 14 located at the sides of the machines to hold the type basket level in either of its case shifted positions.

Adjustably mounted on the sides of the type basket 11 are the arms 16 of which there is one on each side of the machine. These arms are connected by links 16a to arms 17 which are secured to a cross shaft 18 suitably journaled in the frame work. By rocking the shaft 18 counterclockwise, the type basket 11 will be drawn downwardly to the upper case position. For the purpose of effecting this movement of the type basket, there is provided a power operated mechanism which is controlled by a shift key 19 pivoted on the fulcrum wire 20 extending across the machine and acting as a pivot for all of the keys of the keyboard.

This power operating mechanism includes the main power roller 10 which cooperates with the usual cam units operating the type bars (not shown) in the basket 11 and a second power roller 21 mounted on the shaft 22. This second power roller 21 is driven by the main power roller 20 through a belt 23 which passes around pulley grooves formed in the ends of the power rollers 10 and 21.

Pivoted on a cross rod 24 which pivots the front cam units (not shown) which operate the type bars and other devices is a cam unit 25 comprising an assembly including a frame having the general form of a right angle lever, one of the arms of which is connected by a link 26 to a rock lever 27 pivoted at 28 on the main frame work of the machine. An arm of lever 27 is connected by

a pin and slot connection 29 to one of the arms 17 whereby rocking of lever 27 in a counterclockwise direction will result in drawing down the type basket to the upper case position.

The cam unit 25 includes a frame 25a in which a substantially circular cam 25b is eccentrically pivotally mounted at 25c and the cam 25b is provided with a circular cutaway portion 25d which normally confronts the power roller 21 to provide a clearance which normally prevents the cam 25b from being rotated by the power roller 21. When the type basket is in the lower case position the periphery of the cam 25b is clear of the main power roller 10.

The cam 25b is provided with two projections 25e which may take the form of bosses and are located equal distances on diametrically opposite sides of the pivot 25c of the circular cam 25b. In the normal position of the cam 25b, as shown in Fig. 1, a spring actuated arm 25f engages the side of the lower boss 25e and tends to urge the cam 25b in a clockwise direction. The arm 25f is pivoted at 25g to frame 25a of the cam unit and is urged in a clockwise direction by torsion spring 25h. The cam 25b is also provided with two stop lugs 25i, 25j. Also pivoted at 25g is a detent lever 25k having a bent over lug 25l normally engaging the lug 25i thus preventing the cam 25b from rotating clockwise. The key 19 is provided with an extension 19a having a slot embracing a pin 25m carried by the arm of the detent lever 25k opposite the one carrying the lug engaging 25l.

The operation of these parts will now be explained in detail.

It will be assumed that the operator desires to shift type basket 11 to enable upper case type characters on the type bars to print on the work sheet. To effect this result the operator depresses the shift key 19. This causes the detent lever 25k to rock in counterclockwise direction thereby releasing the lug 25l on the detent lever 25k from the lug 25i. This permits the spring arm 25f to rotate the cam 25b a limited amount in a clockwise direction thereby causing the circular portion of the cam 25b to engage the periphery of power roller 21. The cam 25b is now driven positively by the power roller 21 through half a revolution to the position of Fig. 2. Thus the cam 25b in effect rolls over the periphery of the roller 21 and, on account of the eccentric mounting of the cam 25b on the cam unit frame, causes the frame of the cam unit 25 to be rocked clockwise thereby thrusting upwardly on the link 26 and, through the lever 27, arms 17, and the links 16a, drawing down the type basket to the upper case position.

The case shift key 19 will either be held down by the operator while operating the desired character key or may be locked down by means of the usual shift lock key (not shown).

The lugs 25i, 25j are so located on the cam 25b on opposite sides of the pivot 25c that when the detent lever 25k is operated by the key as aforesaid and held in operated position, it moves out of engagement with the lug 25i into the path of the lug 25j. In other words, the lug 25j is located at a slightly greater distance from pivot 25c but almost diametrically opposite the lug 25i. Thus, when the cam 25b is rotated a half revolution, the lug 25j engages the lug formed in the detent lever 25k, as in Fig. 2, and prevents further rotation of the cam 25b as long as the shift key 19 is held depressed. As a result of the depression of the key the type basket

is shifted positively downward to the upper case position, this operation being effected very smoothly on account of the fact that the cam is circular whereby the acceleration and deceleration of the cam unit frame is slow. Likewise the stopping of the type basket is effected slowly, thus preventing the type basket stop 15 from striking the post 14 with a slam.

If now the operator releases the shift key 19, the detent lever 25k will be rocked back to its original position, shown in Fig. 1, and will thereby remove the lug on the detent lever 25k from engagement with the lug 25j. This permits the cam 25b to engage power roller 10 and to make another half revolution, positively restoring the parts to the position of Fig. 1. Thus the type basket is moved positively back to the position of Fig. 1 but the initial and terminal velocities of the type basket will be low preventing the stop screw 13 from slamming against the post 14.

In order to yieldingly hold the lever 27 in either of its shifted positions there is provided a toggle spring 30 which engages pins carried by the end of lever 27 moving the bar and slot connection 29 and by the main frame, respectively. The spring 30 also causes the lever 27 to move a little further in each direction than the lever is actuated by the cam unit 25 for the purpose of carrying the cam unit to the position of Fig. 1, in which the cam 25b is clear of the power roller 10, or to the position of Fig. 2, in which the cam is clear of the power roller 21. Without spring 30, the cam might drag on one or the other of the power rollers 10 and 21 resulting in wear of the power roller. This spring is helpful in preventing wear because the surface of the power roller is usually rubber which would have a groove worn in it if the cam dragged.

One of the main advantages of the mechanism described above is that the type basket shift mechanism can be simplified. Heretofore it has been customary to use the shift mechanism disclosed in Patent No. 1,945,097 in which the cam unit actuates a T-lever which is moved to alternate operative positions by a connection to the shift key. This construction was made necessary by the fact that the shift cam unit usually has a double-lobed cam, and operates positively in only one direction, being restored by a spring. On the other hand, the type basket must be moved first to one position and then back to its original position in an interrupted cycle requiring that the T-lever be used to positively move said type basket first in one direction and then in the other with two identical movements of the cam unit. With the present invention the type basket can be moved positively in one direction by a half cycle of operation of the cam unit and then moved positively in the other direction by another half cycle without the necessity for using a T-lever which is shifted by the key between half cycles. Thus, relatively simple connections between the cam unit and the shift mechanism may be used in the present case with a more positive action since the action is more direct and much simpler.

Another advantage of the mechanism disclosed herein is that the touch required to actuate the shift key is greatly lightened and is no greater than the touch required for the character keys because of the elimination of the T-lever which imposes a certain amount of additional load on the shift key.

A further advantage is that the mechanism

operates much more smoothly by reason of the circular shape of the cam 25b, causing the cam to function like an eccentric in imparting motion to the cam unit. This arises from the fact that the cam 25b is picked up and released by the power roller in substantially the dead center position of the eccentric with respect to the power roller. It is well known that the departure of an eccentric from and its approach to the dead center position is effected with slow motion. It follows that the type basket will be brought to a stop smoothly before the power roller loses complete control of the cam 25b.

A distinct advantage of the mechanism is that the operation of the type basket is more closely synchronized with the operation of the shift key. When the shift key is in the position of Fig. 1, the type basket must necessarily be in lower case position since only in this position is the stop lug 25i, which determines the position of the cam in Fig. 1, in engagement with the lug on lever 25k. In other words, if the shift key were merely flipped with the finger and not held down, the cam 25b will always make a complete revolution thus drawing the type basket down to its upper case position and then immediately thrusting it back to lower case position. In the shift mechanism disclosed in the above patent, if the key is flipped instead of being held down, the cam unit will draw the type basket down to upper case position but the T-lever will be restored immediately along with the key with the result that the second operation of the cam unit merely tends to repeat the effect on the type basket and leaves the type basket in the upper case position.

While there have been shown and described and pointed out the fundamental novel features of the invention, as applied to a single embodiment, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a power operated typewriter, a case shiftable part, a main power roller, a second power roller; a cam unit connected to said case shiftable part and including a cam alternately operatively engageable with both said power rollers to effect both a positive shift of said case shiftable part and a positive restoring movement of said part, and including releasable means for causing the alternate engagement of said cam with said power rollers; and a shift key for controlling the releasable means.

2. A power operating device for typewriters and the like comprising a pair of power drivers, a member adapted for actuating a device of the typewriter, cam means mounted on said member for engagement with one or the other of said drivers; means to cause the cam means to engage and be positively operated by first one and then by the other of said drivers, said cam means, when engaged with said power drivers, coupling the first member to the drivers for operation by the latter; and means for controlling the causing means.

3. In a power operated typewriter, a part to be actuated, a pair of power rollers; means connected to said part and mounted between said power rollers, including a rockable member and a coupling member carried thereby adapted to

engage and be operated first by one and then by the other of said power rollers, said coupling member when engaged with one power roller being operated thereby to rock said rockable member to actuate said part and at the same time carry the coupling member into a position to engage the second power roller for operation thereby, said coupling element, when engaged with the second power roller, rocking said rockable member to a position in which the coupling member may again be engaged with the first power roller and, simultaneously with said second rocking movement, actuating said part; means to cause said coupling member to engage said power rollers in the alternate positions of the rockable member, and a key for controlling the last named means.

4. A power mechanism for typewriters comprising a pair of power operators, a support member pivoted for rocking movement from each of said operators toward the other, an element carried by said support member and adapted to couple said support member to said operators for operation by one or the other of said operators according to the position to which the support member is rocked, means for operatively engaging the coupling element with one of the power operators in either of the rocked positions of said support member, and a key for controlling the engaging means.

5. In a power operated typewriter, a pair of rotary power operators; means adapted to be operated by said operators and mounted for movement between alternate positions from one of which positions said means may be moved by one of said operators to the other alternate position in which said means may be operatively coupled with the other operator, said means including a rotary element engageable with the respective operators in said positions to render said means operable by the respective power operators, and including means for rotatably engaging said element with said operators; and means for rendering the engaging means effective.

6. A power mechanism for typewriting machines comprising a pair of power rollers, a frame pivoted to swing between said power rollers; a substantially circular member eccentrically pivoted to said frame between said rollers and adapted to engage and be actuated by one of said rollers, according to the position of said frame, when said member is initially rotated a small amount, said member, when rotated by either roller, causing said frame to move to a position to permit similar rotative engagement with the other roller for restoration of said frame to its initial position; means to initially rotate said member, releasable means coacting with said member to normally prevent said initial rotation, and means for operating the releasable means in both positions of said frame.

7. A power operating mechanism for typewriters comprising a pair of power rollers, a cam frame mounted to swing between said power rollers, a cam rotatably mounted on said frame between said rollers so as to be engageable with one or the other of said rollers according to the position of said frame; means to impart to said cam a partial rotation to enable it to be further rotated by one of said power rollers to thereby rock said frame to move the cam toward the other power roller, said rotation by said one power roller restoring said cam to the influence of said partial rotation means; a detent engag-

ing said cam to prevent said partial rotation in either of the positions of said frame, and means for releasing said detent operable in either of the positions of said frame.

8. In combination with a shift mechanism having a part mounted for movement between two case shift positions, a pair of separate power actuating members; means connected to said part and engageable with both of said members for operation by one or the other of said members according to the position of said part and including a coupling element and means to engage the coupling element with said members; and means for rendering the engaging means effective in either position of said part, including a key movable in one direction to cause the coupling element to engage one actuating member in one position of the case shiftable part and movable in another direction to cause the coupling element to engage the other actuating member in the other position of the case shiftable part.

9. In a machine of the class described, a pair of separate power operators, a device alternately engageable with one or the other of said operators and, when engaged with either operator, being actuated thereby to a position to be en-

gaged by the other operator, said device having means engageable with said operators to couple said device to one or the other of said operators according to the position of said device; and means for causing the engagement of the coupling means with one of said operators in either position of said device, including a key movable in one direction to render the causing means effective with said device in one position and movable in another direction to render the causing means effective in the alternate position of said device.
